UNITED STATES PATENT OFFICE.

CHARLES L. LEE AND THOMAS C. VAN DEGRIFT, OF DAYTON, OHIO, ASSIGNORS TO GENERAL MOTORS RESEARCH CORPORATION, OF DAYTON, OHIO, A CORPORATION OF DELAWARE.

FURNACE.

Application filed February 11, 1924. Serial No. 691,928.

To all whom it may concern:

Be it known that we, CHARLES L. LEE and THOMAS C. VAN DEGRIFT, both citizens of the United States of America, residing at 5 Dayton, county of Montgomery, and State of Ohio, have invented certain new and useful Improvements in Furnaces, of which the following is a full, clear, and exact description.

10 This invention relates to apparatus for treating bodies which are introduced into and removed from a furnace heating chamber while the heating of the chamber is continued.

15 One of the objects of the invention is to minimize the loss of heat from the furnace when the furnace door is opened to permit removal of articles from the furnace or to introduce other articles to be heated.

20 A further object is to protect the operator from excessive heat when the furnace door is opened.

Another object is to facilitate removal of 25 articles from the furnace and the placing therein of other articles to be heated.

Further objects and advantages of the present invention will be apparent from the following description, reference being had to the accompanying drawings, wherein a 30 preferred embodiment of one form of the present invention is clearly shown.

In the drawings:

Fig. 1 is a sectional view of a furnace embodying the present invention the furnace door being open and the article supporting 35 spindles being in forward position to permit placing thereon the work to be heated.

Fig. 2 is a sectional view of the mechanism for moving the carriage which supports the work spindles.

Fig. 3 is a sectional view of the furnace with the door closed and the spindles retracted to work heating position.

Fig. 4 is a mechanical diagram showing 45 the manner of driving the spindles by one electric motor mounted on the spindle carriage.

Referring to the drawings, 20 designates a furnace having a heating chamber 21 and a vestibule 22 which is separated from the chamber 21 by a partition 23 having apertures 24. The chamber and vestibule are lined with refractory material 25 and are jacketed by a body of heat non-conducting 50 material 26 enclosed by a metal casing 27.

The vestibule is closed by a door 28 attached to a cable 29 leading over pulleys 30 and connected with an eccentric pulley 31 mounted on a shaft 32 supported below tracks 33 (one shown) mounted on legs 34 60 and 35 at the rear of furnace 20.

Tracks 33 support a carriage 40 mounted on wheels 41. Carriage 40 supports bearing brackets 42 and 43 which support four shafts 44, 45, 46, and 47. Each shaft supports a spindle 48 of heat resisting material which extends through a tube 49 in the furnace wall, and is in alignment with one of the openings 24 in partition 23. Each spindle 48 is detachable from its shaft and it 70 is driven through a pin-and-bayonet-slot connection 50.

Referring to Fig. 4 the spindles 44, 45, 46, and 47 are connected with gears 54, 55, 56, and 57 respectively all driven by a gear 51 75 on shaft 52 carrying a worm gear 53. Gear 53 meshes with a worm 58 on shaft 59 driven by motor 60 mounted on carriage 40.

Carriage 40 is provided with a depending bracket 61 (see Fig. 2) attached to a rod 80 62 connected with a piston 63 reciprocable in a cylinder 64 supported between the tracks 33. The ends of cylinder 64 are connected by pipes 65 and 66 with a valve body 67 carrying a rotatable valve 68 having two 85 separate passages 69 and 70. Valve body 67 is provided with an exhaust port 71 and is connected with a fluid pressure (such as air) supply by a pipe 72. Valve 68 is mounted on a spindle 73 carrying a gear 74 90 which meshes with a gear 75 located on shaft 76 which extends through a tube 77 in furnace 20 and terminates in a pedal 78.

At 80, the bracket 61 is attached to a cable 81 connected with a pulley 82 on 95 shaft 32.

The walls of the chamber 21 of the furnace support electrical heating coils 90 by which the chamber 21 is heated.

To operate the furnace, the treadle 78 is 100 moved so that air will be admitted to the left end (as viewed in Fig. 2) of the cylinder 64 to cause the carriage 41 to be moved to the spindle loading and unloading positions as shown in Fig. 1. The movement of the spindles 48 to this position causes the door 28 to be lifted from the furnace opening. This is accomplished by virtue of the cable connection between the carriage 40 and the pulley 82 and the cable connection be- 110

tween pulley 31 and door 28. As the carriage 40 moves to the right, as viewed in Fig. 1, the cable 81 will pull the pulley 82 in a clockwise direction. The pulley 31, moving from the position shown in Fig. 3 to that shown in Fig. 1 will wind up the cable 29 and thus elevate the door.

Each of the work spindles 48 project through an opening 24 into the loading 10 vestibule 22. The work, such as an iron cylinder 100 to which copper fins 101 are to be brazed by a process disclosed in the co-pending application of Charles F. Kettering, Serial No. 514,014, filed November 9, 15 1921 (case 74), is mounted on a spindle 48, the opening 24 being large enough to receive the work. The cylinder may be provided with a flange 102. It is apparent that the fins 101 and the flange 102 as well as the 20 spindle 48 and cylinder 100 will materially obstruct the flow of heat from the chamber 21 through the opening 24.

When the spindles 48 are loaded; the 25 pedal 78 is moved so that the valve 68 will be located as shown in Fig. 2, to admit fluid pressure to the right hand end of cylinder 64, whereupon the carriage 40 will be moved to the work heating position shown in Fig. 3 and the furnace door 28 will be 30 moved to close the furnace opening.

The spindles may be rotated when desired by operating the electric motor 60, regardless of the position of the carriage. In the process disclosed in the application referred 35 to, it is desirable to rotate the work while being heated in order to secure even heat distribution and to prevent segregation of the bonding material used to join the copper fins to the iron cylinder wall. After the 40 bonding temperature is reached, the carriage is moved to the position shown in Fig. 1, while the spindles 48 are still rotating. The cylinders cool while being rotated to a 45 temperature below the melting point of the bonding material, so that even distribution of the bonding material is obtained.

The cylinder 100 therefore acts as a door or baffle tending to prevent the escape of heat from the chamber 21 through one of 50 the openings 24 in the partition 23, at the time the door 28 is elevated. Therefore the escape of heat is minimized and the furnace operator may attend the furnace with less discomfort. Since the carriage moves the 55 spindles 48 to work heating position the operator is required to approach the furnace opening only sufficiently to remove work from or to place work upon the ends of the spindles when they are located in the 60 vestibule 22 as shown in Fig. 1.

While the form of embodiment of the invention as herein disclosed, constitutes a preferred form, it is to be understood that other forms might be adopted, all coming 65 within the scope of the claims which follow.

What is claimed is as follows:

1. Heat treating apparatus comprising in combination, a furnace including a heating chamber; a vestibule separated from the heating chamber by an apertured partition; 70 a door for the vestibule; and common means for moving work pieces from the heating chamber into the vestibule and opening the door of the vestibule.

2. Heat treating apparatus comprising in 75 combination, a furnace including a heating chamber; a vestibule separated from the heating chamber by an apertured partition; a door for the vestibule; means for moving treated work pieces from the heating chamber into the vestibule and work pieces to be treated from the vestibule into the heating chamber; and means associated with the work-piece-moving means for opening and closing the vestibule door when the work pieces are moved into the vestibule and heating chamber respectively.

3. Heat treating apparatus comprising in combination, a furnace including a heating chamber; a vestibule separated from the heating chamber by an apertured partition; a carriage having two positions; work-piece-supporting spindles rotatably carried by the carriage, and extending through one wall of the heating chamber so that their free ends are in the heating chamber when the carriage is in its retracted position; means on the carriage for rotating the spindles; and means for moving the carriage into its forward position whereby the spindle ends will be moved from the heating chamber through the apertured partition into the vestibule, the main body of the spindles extending through the heating chamber while in this 100 position.

4. Heat treating apparatus comprising in combination, a furnace including a heating chamber; a vestibule separated from the heating chamber by an apertured partition; a door for said vestibule; a carriage having retracted and forward positions; work-piece-carrying spindles rotatably supported on the carriage and extending through the one wall of the heating chamber so that the free ends of the spindles are in the heating chamber when the carriage is in its extreme 110 retracted position; spindle-rotating means mounted on the carriage; means for moving the carriage into its forward position and simultaneously opening the vestibule door and for returning the carriage to its retracted position and closing the vestibule door.

5. Heat treating apparatus comprising in combination, a furnace including a heating chamber; a vestibule separated from the heating chamber by an apertured partition; a door for the vestibule; and means for simultaneously opening the door and moving the work pieces from the heating chamber 125 130.

into the vestibule and holding said work pieces in such a position in the vestibule so that they will act as a baffle to prevent escape of heat from the heating chamber while the 5 vestibule door is held open.

6. Heat treating apparatus comprising in combination, a heating chamber provided with an opening; a door for said opening; a work carrier located within the heating 10 chamber; means for moving the work carrier toward the heating chamber opening and opening the door to permit removal of the treated work and application of new work to be treated and for retracting the 15 work carrier from the opening and closing the door.

7. Heat treating apparatus comprising in combination, a furnace having a heating

chamber, a vestibule separated from the heating chamber by an apertured partition, 20 and a door for the vestibule; and means for moving work pieces through said apertured partition and for rotating said work.

8. Heat treating apparatus comprising, in combination, a furnace having a heating 25 chamber, a vestibule separated from the heating chamber by an apertured partition, and a door for the vestibule; and means for moving work pieces through said apertured partition and for rotating said work, and 30 for operating said door.

In testimony whereof we hereto affix our signatures.

CHARLES L. LEE.
THOS. C. VAN DEGRIFT.
